ROCK DRILL

Edward F. Terry, Phillipsburg, N. J., assignor to
Ingersoll-Rand Company, Jersey City, N. J., a
corporation of New Jersey

Application May 29, 1935, Serial No. 23,961

3 Claims. (Cl. 121—31)

This invention relates to rock drills of the reciprocating piston type, and more particularly to the piston assembly for rock drills equipped with rifle bar rotation mechanism for effecting 5 rotation of the working implement which the piston actuates.

One object of the invention is to minimize the weight of the piston.

Another object is to equip the piston with a composite rifle nut of which the component parts are so constructed and arranged with respect to each other as to preclude accidental loosening or withdrawal of the rifle nut from the piston.

Other objects will be in part obvious and in 15 part pointed out hereinafter.

In the drawing accompanying this specification and in which similar reference characters refer to similar parts,

Figure 1 is a sectional elevation of so much of 20 a rock drill as will serve to illustrate the invention and a practical application thereof, and

Figure 2 is a transverse view taken through Figure 1 on the line 2—2.

Referring more particularly to the drawing, 25 20 designates a rock drill comprising a cylinder 21 and a back head 22 which may be secured to the cylinder 21 in any suitable manner.

The cylinder 20 is bored to provide a piston chamber 23 for the accommodation of a reciprocating hammer piston 24. The piston 24 is of 30 the differential type having a head 25 which controls an exhaust port 26 intermediate the ends of the piston chamber, and a stem 27 on the piston extends slidably through a front cylinder washer 28 in the end of the cylinder.

The stem 27 is provided with the usual flutes 29 which slidably interlock with a suitable chuck device (not shown) whereby a working implement (not shown) may be guided and interlocked 40 in a manner well understood to enable the rotary movement of the piston to be transmitted to the working implement for shifting it between blows of the piston 24.

In the rearward end of the cylinder 21 is an 45 enlarged bore 30 to accommodate valve mechanism 31 and rotation mechanism 32. The valve mechanism 31, of which only the chest 33 is shown, lies adjacent the rear end of the piston chamber 23 to serve as a closure for the piston chamber. Interiorly, the valve chest 33 may be 50 formed to accommodate any suitable valve (not shown) for distributing the pressure fluid to the ends of the piston chamber 23, a front inlet passage 34 being shown extending through the

cylinder from the valve mechanism 31 for this purpose.

The rotation mechanism 32, which is illustrated as being of a well known type, comprises a rifle bar 35 that extends through the valve mechanism 31 and interlockingly engages a rifle nut 36 disposed in a recess 37 in the head 25. A head 38 on the rifle bar carries the usual spring-pressed pawls 39 adapted to engage teeth 40 of a ratchet ring 41 for determining the direction of rotation of the rifle bar 35 and thus of the piston 24 and the devices connecting the piston with the working implement.

The rifle nut 36, constructed in accordance with the practice of the invention and which 15 may be constructed of bronze, is internally fluted as is customary for engagement with the rifle bar 35. In length it preferably equals the depth of the recess 37 so that when occupying its assembled position in the piston the innermost end 20 surface 42 of the rifle nut seats upon the bottom 43 of the recess 37 and the outermost end of the rifle nut 36 will then lie flush with the rear end of the piston 24. The wall of the rifle nut 36 is of only sufficient thickness to enable the rifle 25 nut to withstand the thrust imparted thereto by the rifle bar at the instant of reversal of the piston 24, and the diameter of the nut is very considerably smaller than the diameter of the recess 37 to permit the interposal of a sleeve 44 30 between the nut 36 and the skirt or wall of the piston head 25.

On the periphery of the nut 36 are threads 45 for engagement with corresponding threads 46 in the sleeve 44. The nut 36 is threaded into the 35 sleeve 44 through the innermost end of the sleeve and has a head 47 which is provided with a bevelled surface 48 to frictionally engage a bevelled surface 49 in the sleeve 44. Thus, when the nut 46 is threaded tightly into the sleeve 44 the bevelled surfaces 48 and 49 may be drawn into tight 40 frictional engagement with each other to assist in holding these elements against separation.

The sleeve 44 is preferably constructed of aluminum, a phenol formaldehyde condensation product or other material possessing the quality of low specific gravity as compared with the material of which the rifle nut 36 and the piston 24 are constructed. On the periphery of the sleeve 44 are threads 50 to engage the threads 51 in the 50 recess 37 for securing the sleeve 44 to the piston 24. The threads 45 and 50 on the rifle nut 36 and sleeve 44, respectively, are of opposite hand so that a thrust of the rifle bar imparted to the rifle nut 36 tending to draw the bevelled surfaces 55

48 and 49 tightly together will also tend to thread the sleeve 44 more tightly into the piston 24.

For example, if it be intended to rotate the piston 24 in a clockwise direction, as Figure 1 is viewed, the threads 45 on the nut 36 extend in a right hand direction and the threads 50 on the sleeve 44 extend in a left hand direction. Thus, as the piston moves rearwardly, and during which motion rotation of the piston and devices 10 interlockingly engaging the piston are rotated, the thrusts resulting from the movement of rotation will cause the sleeve 44 to be pressed tightly against the shoulder of the nut 36 and the end 42 of the nut to be pressed tightly against the 15 bottom surface 43 of the recess 37.

In practice, the present invention has been found to be highly desirable as a means for minimizing the weight of the piston assembly without requiring the use of a piston head 25 of such dimensions as to reduce the pressure areas of the piston to impractical sizes. By employing an aluminum sleeve as a medium for binding the rifle nut 36 to the piston the end areas of the 20 piston may be held to known practical dimensions and at the same time the weight of the piston assembly will be considerably decreased. In the case of an aluminum sleeve 44 or one constructed of a product of phenol formaldehyde condensation the weight of the sleeve will be approximately 25 only one-third of the material which it displaces. Thus are obtained the desirable qualities of durability and lightness of weight of the 30 piston.

piston assembly, and the piston may at the same time be sufficiently rugged throughout to fully withstand the severe usage to which it is subjected.

I claim:

1. In a rock drill, the combination of a piston having a recess and a rifle bar extending into the recess, a sleeve threaded into the recess, a beveled seating surface on the sleeve, a rifle nut for the rifle bar threaded into the inner end of 10 the sleeve and seating upon the bottom of the recess, and a beveled surface on the rifle nut frictionally engaging the seating surface to prevent withdrawal of the rifle nut from the sleeve.

2. In a rock drill, the combination of a piston 15 having a threaded recess and a rifle bar extending into the recess, a sleeve having external threads to engage the threads of the recess and having internal threads of opposite hand to the external threads, a rifle nut threaded into the sleeve, and 20 cooperating portions on the sleeve and the rifle nut to prevent withdrawal of the rifle nut from the sleeve.

3. A piston assembly for rock drills having rifle 25 bar rotation mechanism, comprising a piston having a threaded recess, a rifle nut in the recess having external threads of opposite hand to the threads of the recess, and an aluminum sleeve 30 threaded into the recess and being threaded connected to the rifle nut for securing the rifle nut to the piston.

EDWARD F. TERRY.
